Primary Examiner — Cynthia Ramirez*(74) Attorney, Agent, or Firm* — Ryan Kromholz & Manion, S.C.(57) **CLAIM**

The ornamental design for a laundry cart hanger bar, as shown and described.

DESCRIPTION

FIG. 1 is a perspective view of the laundry cart hanger bar showing my new design;

FIG. 2 is another perspective view thereof;

FIG. 3 is a rear elevation view;

FIG. 4 is a front elevation view;

FIG. 5 is a top plan view;

FIG. 6 is a bottom plan view;

FIG. 7 is a right side elevation view; and,

FIG. 8 is a left side view thereof.

The broken lines in FIG. 1 are included only for the purpose of illustrating environmental structure and form no part of the claimed invention.

The broken away symbols in FIGS. 1, 2, 3, 4, 7 and 8 indicate the appearance of any portion of the article between the break lines forms no part of the claimed design.
